CLAIM

The ornamental design for a removable insole, as shown and described.

DESCRIPTION

FIG. 1 is a front, right, and top perspective view of a removable insole, showing my new design;

FIG. 2 is a rear, left and bottom perspective view thereof;

FIG. 3 is a perspective view thereof shown in disassembled condition;

FIG. 4 is a top view thereof;

FIG. 5 is a bottom view thereof;

FIG. 6 is a left side view thereof;

(Continued)

FIG. 7 is a right side view thereof;
 FIG. 8 is a rear view thereof; and,
 FIG. 9 is a front view thereof.
